UNITED STATES PATENT OFFICE

ANDREW B. CLARK, OF THOMASVILLE, GEORGIA, ASSIGNOR OF ONE-HALF TO JUDGE
ROSCOE LUKE, OF THOMASVILLE, GEORGIA

NEEDLE THREADER

Application filed November 21, 1929. Serial No. 408,795.

This invention relates to a needle threader, one of the objects being to provide a simple and efficient device by means of which a thread can be directed through the eye of a needle and looped so that the free end of the thread can be grasped readily and said thread drawn through the needle for a desired distance.

Another object is to provide a structure of this character which serves to house a spool of thread to be used with the threading device, it being possible to change the thread readily whenever desired.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawing the preferred form of the invention has been shown.

In said drawing,

Figure 1 is a view partly in side elevation and partly in section of the complete device.

Figure 2 is a section on line 2—2, Figure 1.
Figure 3 is an enlarged section on line 3—3, Figure 1.

Figure 4 is a vertical longitudinal section through one end portion of the threader.

Figure 5 is a section on line 5—5, Figure 4, a needle being shown in position in the threader during the first step of the threading operation.

Figure 6 is a view through a portion of the threader showing the thread looped as the needle begins its movement off of the threading tongue.

Figure 7 is a view similar to Figure 6 showing the needle withdrawn from the threader and the threading operation partly completed.

Figure 8 is a view similar to Figure 7 showing the completion of the threading operation.

Figure 9 is a view partly in elevation and

partly in section showing a modified form of the device.

Figure 10 is a central vertical section through one end.

Figure 11 is an end view showing the relative positions of the parts at the beginning of a threading operation.

Figure 12 is a section on line 12—12, Figure 10, showing the positions of the parts at the second stage of the threading operation.

Figure 13 is a view similar to Figure 12 showing the third stage of the threading operation.

Figure 14 is a view similar to Figures 12 and 13 showing the relative positions of the parts when the needle has been brought back close to its point of starting.

Figure 15 is a similar view showing the positions of the parts after the needle has been withdrawn with the thread extending through the eye thereof.

Referring to the figures by characters of reference, 1 designates a container in which is located a stem 2 projecting upwardly from the bottom thereof. The container has a removable cover 3 and secured in this cover is a shank 4 the lower portion of which is tubular as indicated at 5 so that, when the cover is placed in position, this shank will slide onto and house the stem 2. A guide in the form of a hook or an eye 6 is arranged within the container 1 and an outlet opening 7 is provided in the cover 3. A spool indicated at 8 is adapted to be mounted on the shank 5 after it has been placed on stem 2 and the thread T extending from the spool is adapted to be inserted through the guide 6 and the opening 7 so that the free end thereof will project outside of the casing or container 1.

The outer end of the shank 4 is attached to the body 8 of the threader. This body has a tubular end portion 9 formed with a longitudinal slot 10 which extends into the body from one end. A cap 11 is removably mounted on the tubular end of the body and is also provided with a longitudinal slot 12. This slot is adapted to register with slot 10 and extends across the end of the cap as shown at 13.

Secured at one end in the body 8 is a thin

leaf spring 14 the free end of which is pointed as shown at 15 and projects through the slot 13. This spring has a slot 16 adjacent the free end thereof. The spring is so proportioned that it can be inserted into the eye E of a needle N.

Extending inwardly from the tubular portion of the body 8 is a transverse series of hooks 17 the points of which are pointed inwardly away from the open end of the body. 10 These hooks are arranged above the spring strip as indicated in Figure 3.

An opening 18 is provided in the tubular portion of the body 8 and the thread T is 15 adapted to be inserted through this opening and through the slot 16 in spring strip 14, the free end of the thread being extended laterally through the slots 10 and 12. When it is desired to thread a needle the eye portion of 20 the needle is placed on the pointed end of the spring strip 14. The needle is then pressed backwardly on said strip, the eye portion of the needle passing through the slot 13 and longitudinally of the slots 10 and 12. As the 25 eye portion of the needle passes over the slot 16 it will engage the thread and press it backwardly within the tubular body to form a loop as indicated in Figures 4 and 5. The needle is then pushed toward the pointed end 30 of spring strip 14 and as the eye portion frictionally engages the looped thread, said loop will be caused to open wide because of the slack in the thread. See Figure 6.

Following the foregoing, the needle is 35 completely withdrawn from the spring strip 14 and during this operation the looped thread will catch in one or more of the hooks 17, thereby causing a portion of the loop to be retained in the tubular body after the needle 40 has been withdrawn and as shown in Figure 7. Continued pull on the needle will withdraw 45 the free end of the thread from engagement with the hook as shown in Figure 8. The thread can then be grasped, a desired length pulled from the spool, and the needle is then ready for use.

In Figures 9 to 15 inclusive a modified construction of the device has been illustrated. In these figures, 19 designates the container 50 for holding the spool S on which is wound the thread T. A guide 20, which can be in the form of a coiled wire, is arranged in the container for sliding engagement by the thread.

The container has a removable cover 21 55 provided with spaced disks 22 and 23. These disks are separated by a spacing strip 24 located between the lower halves thereof. The upper halves of the disks have their edges outturned and spaced from the wall of the cover to provide an arcuate clearance indicated at 25. These free edges are outturned 60 as shown at 26 and secured to disk 23 is a spring finger 27 the free end of which normally bears against the disk 22. This finger 65 is disposed substantially radially of the disks

although inclined laterally as shown in Figure 10.

The periphery of the cover 21 is cut away at one end of the clearance 25 as shown at 28 and projecting through this cut away portion or opening is the pointed free end of a flat spring strip 29. This strip is bowed from end to end and is extended longitudinally of the clearance 25 between the periphery of the cover 21 and the margin of the disk 23. The spring is fastened at that end remote from the opening 28 at a point beyond the end of the clearance 25 as shown at 30.

In practice, the thread T is threaded through an opening 31 in the spring 29 and is 30 drawn downwardly within the clearance 25 between the outturned free edge 26 of disk 22 and the inner disk 23.

The free end portion of the thread is held gripped against the periphery of the cover at a point substantially diametrically opposite the opening 28. Thereafter the eye portion of a needle N is placed on the free end of the spring strip 29 and is slid longitudinally of the strip. This will cause the thread T to be looped about 45 the end portion of the spring strip 29 as shown in Figure 11. As the needle is moved farther to the right, the portion of the thread extending between the disks will be looped about the finger 27 as shown by broken lines 50 in Figure 11.

As the needle continues to move to the right the loop L thus formed will be pulled off of the finger as in Figure 12 while another portion of the thread, indicated at L', is 55 drawn across finger 27.

Needle N is then moved to its extreme right-hand position as shown in Figure 13 so that loop L which had previously been formed about and pulled from finger 27 will be left unsupported in the space between the disks while the portion L' of the thread is pulled 60 downwardly off of the end of the finger 27. The needle is then started backwardly and during this movement along the spring 29 the portion L' will be looped backwardly over 65 finger 27 while the slack in the loop L will be gradually taken up as shown in Figure 14.

When the needle is ultimately withdrawn from the end of the spring 29, as shown in Figure 15, that portion of the thread extending from the needle to the spool will be pulled 70 out of the opening in the spring strip 29 while the free end portion of the thread will be pulled longitudinally through the eye of the needle and around finger 27 with the result that the needle will be completely threaded.

What is claimed is:

1. In a needle threader, the combination 75 with a tubular body having a needle-receiving opening, of a slotted spring strip seated in the body and extending therebeyond for the reception of a thread, and means within the body for engaging and restraining a loop of thread when formed in the tubular body. 130

2. A needle threader including a tubular body having a needle-receiving slot, a slotted spring strip secured in the body and extending therebeyond for insertion into the eye of a needle, and projecting means within the body for engaging and restraining a loop formed of thread in the body.
  3. A needle threader including a tubular body having a needle-receiving slot, a spring strip secured in the body and projecting therefrom, said strip having a thread-receiving slot and being insertable into the eye of a needle, said strip being adapted to cooperate with the eye portion of a needle when the needle is moved therealong to form a loop of a thread extending through the slot in the strip, and means in the body for engaging the loop to restrain it during withdrawal of a needle from the strip.
  4. A needle threader including a tubular body having a needle-receiving slot extending longitudinally thereof, a relatively thin spring strip secured at one end in the body, said strip being slotted for the reception of a thread and having a pointed end for insertion into the eye of a needle, and a member supported within the body for engagement with a loop of thread when formed in the body by the movement of the needle relative to the strip.
  5. A needle threader including a container, thread-holding means therein, and means carried by the container for threading a needle with said thread, said means including a structure having a needle-receiving clearance, a slotted spring strip secured at one end in the structure and having its other end projecting from the structure for insertion into the eye portion of a needle, and a member supported in the structure adjacent to the strip, said strip constituting means for cooperation with the eye portion of a needle to form a loop in a thread and to bring the loop into engagement with the member.
- 45 In testimony that I claim the foregoing as my own, I have hereto affixed my signature.

ANDREW B. CLARK.
